SPOUTING TOY WHALE

Frank Garelick, Woodside, N. Y.

Application August 13, 1949, Serial No. 110,177

5 Claims. (Cl. 46—92)

1

This invention relates to new and useful improvements in aquatic toys, and, more particularly, the aim of the invention is to provide a novel and valuable such toy and one adapted to be floatingly supported on a body of water either out of doors or in the home as in a bath tub, for forward propulsion of the toy by spring-motor means therein when manually wound up, and for simultaneously behaving in a manner suggestive of that of some well-known aquatic creature.

As the invention is preferably carried out, the toy is in the form of a whale, and in that connection preferably including a partially hollow body, as one molded from a suitable plastic, with said body representing in miniature the body of an actual whale, and with said body containing not only its own propulsion means, but also containing its own power plant, as said spring-motor, and further carrying an entirely internally disposed means periodically actuated to cause the whale to spout or "blow."

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of the toy constructed in accordance with the present invention and having the center portion thereof broken away to reveal interior constructions.

Fig. 2 is a partial longitudinal horizontal sectional view taken just above the spring driven motor.

Fig. 3 is an enlarged detailed sectional view of a portion of Fig. 1.

The toy in accordance with this invention is comprised of a body 50 molded to simulate a whale. The body 50 is preferably molded of a waterproof water-floatable material with a large cavity 51 extended upward from the bottom thereof, as clearly shown in Fig. 1. The body 50 is proportioned to float on the surface of a body of water, with the level of the water being indicated by the dot and dash line 52.

Fixedly mounted within the large cavity 51 there is a spring operated motor 53 of a well known design. The motor 53 is secured in position by means of rivets 54 passed through lugs 55, formed on the motor 53, and into the top wall of the cavity 51. Extended from one side of the motor 53 there is the usual winding stud 56 which is square in cross section and which is aligned

with a complementary hole 57 formed in the side of the body 50. The end of the winding key is to be passed through the hole 57 and be engaged with the stud 56 for winding up the spring of the motor 53 to store the required energy for the operation of the toy, as will become apparent as the present specification proceeds.

Extending from the other side of the motor 53, there is a driven crank 58 which has mounted thereon inward of its crank portion a large bevel gear 59. The bevel gear 59 in turn meshes with a small bevel pinion 60 fixedly mounted on the inner end of a downwardly and rearwardly inclined shaft 61. The shaft 61 has an intermediate portion rotatively extended through a portion of the body 50 and which terminates in an end located below the body 50 and within the water. A propeller 62 is fixedly mounted on the bottom portion of the shaft 61 to be rotated when the shaft 61 is rotated for driving the body 50 in a forward direction across the surface of the water.

Means is provided for rotatively supporting the shaft 61 in an elevated position in which the bevel pinion 60 will be in engagement with the bevel gear 59. That supporting means comprises a collar 63 fixedly mounted on the shaft 61 closely adjacent the bevel pinion 60. The collar 63 rests against one face of the arm of an L-shaped bracket 64 which has its other arm fixedly secured to the motor 53. The shaft 61 extends rotatively through the arm of the bracket 64 against which the collar 63 rests.

In order to have the propeller 62 located immediately below the longitudinal axis of the body 50 it is necessary to have the motor 53 mounted within the cavity 51 to one side of that longitudinal axis. To offset any unbalance created by that off center mounting of the motor 53 and to cause the body 50 to float evenly on the surface of the water, a weight 65, see Fig. 2, is mounted on the wall of the cavity 51 remote from the motor 53. The weight 65 is secured in position by several rivets 66.

The top portion of the body 50 adjacent the front end thereof is formed with a cavity 67 in which a container 68 is removably mounted. The container 68 is provided to contain soapy water which is to be used to blow bubbles. The container is formed with a filling spout 69 closed by a removable plug 70. The front end of the container 68 is formed with a discharge nozzle 71 having a very small discharge end preventing the contained soapy water from freely discharging therefrom.

The end of the nozzle 71 is in communication with an air passage 72 which extends from a bellows 73 which is to be operated by the spring motor 53, as will become clear as this specification proceeds, for forcing air past the nozzle 71 to draw some of the soapy water from the container 68 and form bubbles therefrom. The action of the air passing through the passage 72 on the end of the nozzle is much the same as that which occurs in a standard atomizer for withdrawing some of the soapy water from the container 68. The end of the passage 72 terminates in a small bowl-like opening 74 at which point the bubbles are formed.

Beneath the container 68, the cavity 67 extends downward into a small recess 75 which traverses the passage 72 and within which a small one-way valve 76 is mounted. The one-way valve 76 is of standard construction and permits air to pass through the passage 72 from the bellows 73 past the nozzle 71 to the opening 74. By the same token, the one-way valve 76 prevents air and soapy water from flowing through the passage 72 into the bellows 73. The one-way valve 76 is retained in position within the recess 75 by means of a plug 77 between the adjacent faces of the container 68 and the one-way valve.

The bellows 73 includes rigid end walls 78 and 79. The end wall 78 is secured to the top wall of the cavity 51 by means of several pins 80. A discharge tube 81 mounted on the end wall 78 has one end in communication with the interior of the bellows 73 and its other end projected into the passage 72 for conveying the air expelled by the bellows 73 into the passage 72.

The body 50 is further formed with an air intake passage 82, see Fig. 1, and has a one-way valve 83 mounted in the inner end thereof. A tube 84 extends from the one-way valve 83 and extends through the end wall 78 and communicates with the interior of the bellows 73. The one-way valve 83 is of standard construction and permits the free passage of air to the bellows 73 and prevents air from being expelled from the bellows 73 through the intake passage 82.

The end wall 79 of the bellows 73 is formed with a projecting lug 85 and a link 86 has one end pivotally connected to the lug 85 and its other end pivotally connected to the driven crank 58. Thus, the bellows 73 will be operated when the driven crank 58 is rotating. To guide movements of the end wall 79 with relation to the end wall 78, a long pin 87, which is square in cross-section, has one end attached to the end wall 78 and its other end slidably extended through a complementary opening formed in the end wall 79. The free end of the pin 87 is formed with an enlarged head 88 for preventing the end wall 79 from slipping off the end of the pin 87.

From the foregoing description, it is apparent that a novel toy has been provided in which the motor 53 provides the required power for turning the propeller 62 and for operating the bellows 73 to supply the required air under pressure to form the soap bubbles from the soapy water contained in the container 68.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I

claim as new, and desire to secure by United States Letters Patent is:

1. In an aquatic toy having a floatable body including an interior cavity within which motor means are mounted for propelling the body forwardly, a bellows mounted in the cavity, the body having an air passage extending from the cavity to an enlarged discharge opening at the top of the body, means in said passage restricting the flow of air through said passage to discharge from said discharge opening, said bellows having its discharge connected to the end of said passage which opens into said cavity so that as said bellows is operated air will be forced through said passage past said restricting means, linkage connecting said bellows to the motor means to be operated thereby to force air through said passage, and means continuously feeding water into said passage between said restricting means and said discharge opening so constructed and arranged that the water will be blown out of said discharge opening in an upwardly directed spray by the air forced through said passage.

2. In an aquatic toy having a floatable body including an interior cavity within which motor means are mounted for propelling the body forwardly, a bellows mounted in the cavity, the body having an air passage extending from the cavity to an enlarged discharge opening at the top of the body, means in said passage restricting the flow of air through said passage to discharge from said discharge opening, said bellows having its discharge connected to the end of said passage which opens into said cavity so that as said bellows is operated air will be forced through said passage past said restricting means, linkage connecting said bellows to the motor means to be operated thereby to force air through said passage, and means continuously feeding water into said passage between said restricting means and said discharge opening so constructed and arranged that the water will be blown out of said discharge opening in an upwardly directed spray by the air forced through said passage, said restricting means comprising a one-way valve mounted in said passage.

3. In an aquatic toy having a floatable body including an interior cavity within which motor means are mounted for propelling the body forwardly, a bellows mounted in the cavity, the body having an air passage extending from the cavity to an enlarged discharge opening at the top of the body, means in said passage restricting the flow of air through said passage to discharge from said discharge opening, said bellows having its discharge connected to the end of said passage which opens into said cavity so that as said bellows is operated air will be forced through said passage past said restricting means, linkage connecting said bellows to the motor means to be operated thereby to force air through said passage, and means continuously feeding water into said passage between said restricting means and said discharge opening so constructed and arranged that the water will be blown out of said discharge opening in an upwardly directed spray by the air forced through said passage, said water feeding means comprising a water container set into the top of the floatable body closely adjacent said discharge opening, and a nozzle extended downward from said container and discharging into said passage between said restricting means and said discharge opening.

4. In an aquatic toy having a floatable body including an interior cavity within which motor

means are mounted for propelling the body forwardly, a bellows mounted in the cavity, the body having an air passage extending from the cavity to an enlarged discharge opening at the top of the body, means in said passage restricting the flow of air through said passage to discharge from said discharge opening, said bellows having its discharge connected to the end of said passage which opens into said cavity so that as said bellows is operated air will be forced through said passage past said restricting means, linkage connecting said bellows to the motor means to be operated thereby to force air through said passage, and means continuously feeding water into said passage between said restricting means and said discharge opening so constructed and arranged that the water will be blown out of said discharge opening in an upwardly directed spray by the air forced through said passage, said water feeding means comprising a water container set 20 into the top of the floatable body closely adjacent said discharge opening, and a nozzle extended downward from said container and discharging into said passage between said restricting means and said discharge opening, a filling spout extended upward from said container through which the supply of water in said container can be replenished, and a removable plug closing said spout.

5. In an aquatic toy having a floatable body including an interior cavity within which motor means are mounted for propelling the body forwardly, a bellows mounted in the cavity, the body having an air passage extending from the cavity to an enlarged discharge opening at the top of 35 the body, means in said passage restricting the

flow of air through said passage to discharge from said discharge opening, said bellows having its discharge connected to the end of said passage which opens into said cavity so that as said bellows is operated air will be forced through said passage past said restricting means, linkage connecting said bellows to the motor means to be operated thereby to force air through said passage, and means continuously feeding water into said passage between said restricting means and said discharge opening so constructed and arranged that the water will be blown out of said discharge opening in an upwardly directed spray by the air forced through said passage, and a passage controlled by a one-way valve and extending from said bellows to the outer side of the body for conveying air into said bellows as it is operated.
